UNITED STATES PATENT OFFICE.

THOMAS SHIPLEY, OF YORK, PENNSYLVANIA, ASSIGNOR, BY MESNE ASSIGNMENTS, TO YORK ICE MACHINERY CORPORATION, OF YORK, PENNSYLVANIA, A CORPORATION OF DELAWARE.

EVAPORATOR.

Application filed February 23, 1927. Serial No. 170,894.

This invention relates to refrigeration, and particularly to an evaporator designed for high rates of heat transfer.

In certain prior applications I have described and claimed brine cooling systems in which the brine is circulated through a duct at considerable velocity in contact with an evaporator through which the liquid refrigerant is circulated either as a result of violent ebullition therein, or by means of a power actuated circulating pump. The effect of this forced circulation is greatly to increase the heat transfer rate per square foot of evaporator surface, with a consequent reduction in the size of the evaporator for a given heat load.

Such evaporators must be operated flooded, and since the evaporation of the volatile refrigerant is violent it is necessary to provide for the ready disengagement and discharge of the resulting vapor without the undue entrainment of liquid refrigerant. Unless the vapor is freely discharged from the evaporator it becomes largely gas-bound and there is a consequent reduction of its effective surface area.

It is a relatively simple matter to design on paper an evaporator which offers the necessary short upward flow paths for the disengaged vapor, but such designs do not lend themselves readily to construction with the materials and methods now available, particularly when considerations of strength and maintained gas-tightness are taken into account. For example, it has been proposed to use two practically horizontal headers, the lower one being the liquid supply header and the upper the gas off-take header, and to connect these headers by vertical tubes. Such an evaporator, could it be commercially constructed, would be almost ideal, but it has been found that extreme accuracy in the dimensions of the tubes is necessary, and that as soon as a few tubes are put in place the structure becomes so rigid that the positioning of the remaining tubes becomes exceedingly difficult, and the replacement of a defective tube becomes virtually impossible.

The purpose of the present invention is to produce an evaporator having the advantages characteristic of the type just described, without the inherent manufacturing disadvantages, and incidentally produce an evaporator which can be readily constructed in

sections capable of ready assembly on the job.

Another object of the invention is to produce a structure of this character offering a very large effective surface in proportion to its over-all dimensions, and so designed as not unduly to retard the flow of brine or other liquid in contact with the exterior of the evaporator.

Generally stated, I make use of a lower liquid header and an upper gas or vapor header connected at one end by a vertical chamber which serves as a combined liquid reservoir and suction trap. By making this of sufficient capacity it may also serve as the main receiver of the system, in which case it becomes what is commonly known to the trade as a receiver suction trap. The two horizontal headers are connected by tubes which have a bowed, or preferably a V-shaped form, so as to combine a relatively long flow path through the tubes from the lower to the upper header with a relatively steep flow gradient favorable to the disengagement of vapor from the liquid.

In order to give a favorable angle of entrance of each tube into the two headers, the ends of the tubes are bent to reduce their obliquity to the headers, though it is ordinarily not feasible to bend the tubes to such an extent that they enter the headers with their axes in a line strictly radial to the headers. These tubes are welded in place. Furthermore, the headers are formed in sections which are connected end to end. Thus each evaporator is made up of a plurality of sections, each section consisting of a top header section, a bottom header section, and a group of V-shaped tubes connecting the same. The nature of the joints in the header ordinarily entails a slight interval between successive groups of tubes in a complete evaporator. This effect is avoided, so far as possible, by the use of a reinforced welded butt-joint between successive header sections.

A commercial embodiment of the invention is illustrated in the accompanying drawings, in which

Fig. 1 is an elevation of the evaporator assembled.

Fig. 2 is a plan view of the same.

In Figs. 1 and 2 the general dimensions of the confining duct for the brine are indicated in broken lines, it being understood that the

brine is circulated longitudinally through the duct so that the brine flow is parallel with the top and bottom headers of the evaporator.

5 Fig. 3 is a transverse section through the evaporator showing this on an enlarged scale and showing it in position in the brine confining duct.

10 Fig. 4 is a detail showing the welded joint between two sections of a header, the view being taken in longitudinal axial section through the header.

15 The vertical drum 6, shown in Figs. 1 and 2, serves as a receiver suction trap and extends upward above the upper header of the evaporator, and thus may, if desired, be operated to maintain a static head of liquid ammonia on the entire evaporator. The feed line for liquid ammonia is indicated at 31 and the suction line leading from the drum 6 to the compressor is shown at 32. Extending horizontally from a point near the bottom of the drum 6 are two parallel liquid headers 7. Parallel with and 25 above the headers 7, at a height determined by the vertical dimension of the duct in which the evaporator is to be mounted, are two parallel gas or vapor headers 8. The headers 7 and 8 are made in sections connected by joints, indicated generally in Figs. 20 1 and 2 by the numeral 9. The construction of the joint is shown in detail in Fig. 4, the joint proper 9 consisting of fused metal deposited by a welding process. 30 Alinelement of the two sections is secured by an internal sleeve 10 which assists in stiffening the joint and which enters, to some extent, into the structure of the complete welded joint.

40 Each section of each lower header 7 is connected with the corresponding section of the corresponding upper header 8 by a plurality of tubes 11, each of which is characterized by a bow or bend 12 which gives 45 to the tube as a whole a bowed or V-shape. I prefer to make the bend 12 of a relatively short radius because this increases the length of the tube 11 between headers and simplifies the bending operation, but, obviously, the radius of the bend 12 may be increased, and as it is increased the form 50 of the tube would approach a simple arc.

55 I do not regard the radius of the bend 12 as more than a matter of dimension so far as the broader aspects of this invention are concerned, but for manufacturing reasons, it is believed to be simpler to use a form of tube 11 substantially as illustrated in the drawing.

60 Between each pair of headers 7 and 8 there are three sets of tubes arranged in three planes. The axial plane of the center set passes through the axis of the two headers, and the axial planes of the two side sets 65 are parallel with this plane and at approxi-

mate tangency with the sides of the headers. The spacing is such as to offer continuous clear flow paths between the groups of tubes in the different planes, as is made clearly apparent in Fig. 3. Furthermore, the overall dimension measured across the outside tubes approximates, or at any rate does not materially exceed, the outside diameter of the headers, thus producing a compact unit for mounting in a duct of rectangular cross section.

70 Adjacent both ends each tube 11 is bent to afford a favorable angle of entry into the header. The tubes are welded in place and it is therefore not necessary that they enter 80 in a strictly radial direction relatively to the header. Thus tubes in the middle plane are simply bent in this plane to a slight angle, as indicated at 13 on Fig. 1. This does not cause the tube to enter the header in a strictly 85 radial direction, as it is not desirable to bend the tubes more than is necessary to give a reasonably favorable angle of entrance. The ends of the tubes in the two side planes are bent obliquely, as indicated at 14, the nature 90 of the bend being apparent from an inspection of Figs. 1 and 3. The bend is such that when viewed in cross section (see Fig. 3) the ends of the tubes enter the header in 95 an approximately radial direction.

100 The ends of the tubes project into the headers, as clearly indicated at 15 in Fig. 3. Because of the inclination of the entering portions of the tubes 11 to the axes of the headers 7 and 8, the refrigerant flowing outward in the header 7, will have a natural tendency to enter the tubes 11 and refrigerant vapor discharging into the header 8 from the tubes will discharge with a component of motion in the direction of 105 flow toward the drum 6. This is favorable to rapid circulation of the refrigerant through the evaporator.

110 The upper header 8 is closed at its outer end, as shown at 16. The lower header 7 is provided with an extra section 17, to which no tubes are connected. This is closed as indicated at 18, and is mounted with a slight downward inclination, as is 115 shown in Fig. 1. The purpose of the extra section 17 is to receive and drain away from the header 7 any oil which may enter the drum 6. The connections 19 shown in Fig. 1 are oil take-off connections designed to remove oil from the extreme end of the section 17. There is one section 17 for each of the two headers 7, and also a corresponding oil drain connection 19 for each.

120 While the evaporator described above is suited for various uses, and no necessary limitation to any particular field of use in the refrigerating art is implied, the evaporator offers peculiar advantages in connection with brine coolers in which the brine is 125 circulated through a confining duct at high 130

velocity in contact with the evaporator. It follows from the fact that high velocity brine circulation has the effect of imposing a very heavy heat load upon the evaporator 5 that it is under such conditions that this evaporator develops its marked utility.

In Fig. 3 I show in transverse section a duct of this description. The side walls of the duct are indicated at 20, the top at 21 10 and the bottom at 22. The bottom of an ordinary brine tank is indicated at 23. It will be understood that brine is drawn from the tank and pumped longitudinally through this duct. The broken lines 24 in Fig. 1, and 15 25, in Fig. 2, indicate the approximate dimensions of a duct suitable for use with the evaporator illustrated.

It should be mentioned that the evaporator is shown with sections broken out and 20 that as commonly constructed each section will usually be longer than is shown in the drawing and the over-all length of the evaporator will accordingly be far greater than it is possible to show on a reasonable scale 25 in a Patent Office drawing.

It is desirable that the brine flow from left to right with reference to Fig. 1, so that relatively warm brine enters adjacent the drum 6 and the chilled brine is discharged 30 at the far end of the evaporator adjacent the closed end of the headers. The reason for this is that the most violent ebullition in the evaporator will occur where warm brine is 35 in contact with the walls of the evaporator, and it is obviously desirable to have the violent ebullition occur where a short flow path for the refrigerant from and to the drum 6 is afforded.

While I have shown two units connected 40 to a single drum 6, it is obviously immaterial whether only one or a substantially greater number of such units is so connected. Similarly there are no specific limits as to the 45 number of tubes 11 which are connected to a single header section. The number is determined by shop facilities and erection facilities on the job and will vary in particular cases. The presence of the joints 9 necessitates short intervals between the groups 50 of tubes 11 for each section of the header (see Fig. 1) but by careful designing of the joints 9 it is possible minimize this interval.

What is claimed is,—

1. In an evaporator, the combination of 55 an upper header; an approximately parallel lower header; and a plurality of bowed tubes connecting said headers and nested in and substantially confined to the interval between headers.
2. In an evaporator, the combination of an 60 upper header; an approximately parallel

lower header; and a plurality of tubes bent on short radii to form V-shaped nesting passes between said headers, said passes lying between planes approximately tangent to 65 the sides of said headers.

3. In an evaporator, the combination of an upper header; an approximately parallel lower header; and a plurality of tubes bent on short radii to form V-shaped nesting 70 passes between said headers, said tubes being also bent adjacent their ends so as to enter said headers at a less angle than that made with the header by the tube, the tubes being 75 welded in place.

4. In an evaporator, the combination of a receptacle forming a receiver suction trap; approximately horizontal parallel upper and lower headers extending directly from said trap; and tubes connecting said headers. 80

5. In an evaporator, the combination of a receptacle forming a receiver suction trap; approximately horizontal parallel upper and lower headers extending directly from said trap; and a plurality of bowed tubes connecting said headers and nested in the interval between headers. 85

6. In an evaporator, the combination of a receptacle forming a receiver suction trap; a plurality of approximately horizontal upper headers; a plurality of approximately horizontal lower headers, the upper headers and lower headers being substantially parallel with each other; and a plurality of bowed tubes connecting said upper and lower headers and nested in the intervals between headers, said tubes being arranged to afford continuous flow paths between tubes in the direction of the length of said headers. 95

7. In an evaporator, the combination of a 100 pair of substantially parallel headers; connections for supplying liquid refrigerant to an end of one header and for withdrawing refrigerant from an end of the other header; and a plurality of tubes connecting said 105 headers and projecting at their ends into said headers in general directions toward the supply end of the first header and toward the discharge end of the second header.

8. In an evaporator, the combination of a 110 pair of substantially parallel headers; connections for supplying liquid refrigerant to one end of one header and for withdrawing refrigerant from the same end of the other header; and a plurality of tubes bent upon 115 themselves, connecting said headers and projecting at their ends into said headers in general directions towards the supply end of one and the discharge end of the other.

In testimony whereof I have signed my 120 name to this specification.

THOMAS SHIPLEY.

DISCLAIMER

1,718,313.—*Thomas Shipley*, York, Pa. EVAPORATOR. Patent dated June 25, 1929. Disclaimer filed October 18, 1935, by the assignee, *York Ice Machinery Corporation*.

Hereby enters disclaimer to that part of the claims in said specification which are in the following words, to wit:

“1. In an evaporator, the combination of an upper header; and approximately parallel lower header; and a plurality of bowed tubes connecting said headers and nested in and substantially confined to the interval between headers.

“2. In an evaporator, the combination of an upper header; and approximately parallel lower header; and a plurality of tubes bent on short radii to form V-shaped nesting passes between said headers, said passes lying between planes approximately tangent to the sides of said headers.

“3. In an evaporator, the combination of an upper header; and approximately parallel lower header; and a plurality of tubes bent on short radii to form V-shaped nesting passes between said headers, said tubes being also bent adjacent their ends so as to enter said headers at a less angle than that made with the header by the tube, the tubes being welded in place.”
